HARRY A. FOOTHORAP, OF HARRISBURG, PENNSYLVANIA, ASSIGNOR TO ELLIOTT-FISHER COMPANY, OF HARRISBURG, PENNSYLVANIA, A CORPORATION OF DELAWARE.

PLATEN AND PLATEN EQUIPMENT FOR TYPE-WRITING MACHINES.

1,228,896.

Specification of Letters Patent.

Patented June 5, 1917.

Application filed February 6, 1911. Serial No. 606,931.

To all whom it may concern:

Be it known that I, HARRY A. FOOTHORAP, a citizen of the United States of America, residing at Harrisburg, in the county of Dauphin and State of Pennsylvania, have invented certain new and useful Improvements in Platens and Platen Equipment for Type-Writing Machines, of which the following is a specification.

10 My present invention relates to a novel platen equipment for typewriting machines, and more particularly to a novel arrangement of work holding and impression transferring elements designed to facilitate certain classes of work performed by what are known as flat platen typewriting machines.

15 In the accompanying drawings—

Figure 1 is a plan view of a flat platen equipped in accordance with my invention.

20 Fig. 2 is a bottom plan view thereof.

Fig. 3 is a longitudinal section on the line 3—3 of Fig. 2 with part of the platen length broken out.

25 Fig. 3^a is a detail view partly in section of the tension frame and its support.

Fig. 4 is a section on the line 4—4 of Fig. 2.

Fig. 5 is an enlarged sectional view on the line 5—5 of Fig. 2.

30 Fig. 6 is an enlarged detail sectional view on the line 6—6 of Fig. 2.

Fig. 7 is a perspective view of the platen and its equipment complete with the exception of the machine.

35 Fig. 8 is a side elevation of both end portions of the platen showing the relation of the parts located at said ends, a portion of the machine being indicated in dotted lines and certain of the parts being shown in 40 dotted lines in their shifted positions.

Fig. 9 is a detail sectional view on the line 9—9 of Fig. 8.

45 Fig. 10 is a side elevation of a portion of the right hand side of the platen and machine designed more particularly to show the location and mounting of the line space tabulator stop.

Fig. 11 is a transverse sectional view on the line 11—11 of Fig. 10.

50 Fig. 12 is a detail perspective view of the line space stop.

Fig. 13 is a detail perspective view of the line space stop and the line space stop bar,

portions of both being broken away to better illustrate the construction, and

55

Fig. 14 is a detail perspective view of one of the machine gibs and a portion of the track or rail with which it coats.

The features to which my invention are directed are designed with special reference 60 to the equipment of what is known as the Elliott-Fisher writing, adding and billing

machine of commerce. This machine is exemplified in patents to R. J. Fisher Nos. 562,625 and 573,868 and includes a flat 65

platens 1 disposed along the longitudinal edges of which are tracks 2 for the support

of the typewriting machine proper which includes a main frame 3 fragmentarily shown in Figs. 1, 10 and 11 and designed 70

to travel longitudinally of the platen 1. Upon the main frame 3 is mounted to travel transversely of the platen a carriage 4 fragmentarily indicated in dotted lines in Fig.

1 and supporting printing mechanism in 75 the form of type bars 5 one of which is indicated in Fig. 1. The longitudinal move-

ment of the machine over the platen spaces the lines of writing, letter spacing being ef-

fected by the travel of the carriage trans- 80

versely of the platen on the machine frame. The machine is gibbed to the rails 2 by

gibs 6, as shown in Figs. 11 and 14. Dis- 85

posed longitudinally of the platen adjacent to the left hand rail 2 are two parallel clamps 7 and 8, the clamp 7 being imme- 90

diately adjacent to the rail and vertically movable to clamp the left hand edge of the base or master sheet 9. The inner clamp 8 lies immediately adjacent to the clamp 7 95

and is likewise vertically movable to clamp

the primary work sheet 10 which in differ-

ent classes of work may be a bill, a depart-

mental order sheet, etc.

The work sheet 10 is imposed upon the 95 master sheet 9 and it is desired in the pres-

ent instance to transfer only a limited amount of data from the sheet 10 to the master sheet, as for instance, the digits included in two columns of figures. To effect 100

this transference an endless transfer ele- 105

ment 11 which surrounds the platen longi-

tudinally has its upper run interposed be-

tween the right hand margin of the sheet

10 and the subjacent portion of the sheet 9, 105

a metallic or other tape 12 carried by the

platens being disposed along the right hand edge of the ribbon and over the right hand edge of the primary work sheet to hold the latter close against the platen and thus prevent contact thereof with the machine structure as the latter moves over the platen. The initial adjustment of the master sheet 9 is facilitated by an adjustable top gage in the form of gage pins 13 adapted to form an abutment for the upper or rear edge of the sheet and designed to be received in openings or sockets 14 arranged in series graduated longitudinally of the platen. The initial adjustment of the upper sheet 10 is similarly effected by means of a top gage in the form of pins 15 received in sockets or openings 16 also arranged in series longitudinally of the platen.

In the class of work for which the present equipment is specially intended, a series of entries are made on the master sheet by transference from either the same or different primary sheets. Where different primary sheets are in use it is obviously necessary that each new primary sheet be adjusted with reference to the matter which may have been previously printed on the master sheet. Thus at the initiation of the operation the location of the two sheets is determined, as before stated, by the gage pins 13 and 15, but each new primary sheet must obviously be dropped or advanced the distance of at least one line so that the data will be printed in proper position thereon and will be transferred below the matter already appearing on the master sheet 9. To facilitate this advance of the primary sheet the inner clamping bar 8 is provided with a series of graduations 17 spaced in correspondence with the lines of writing and serving in connection with the upper edge of the sheet 10 to act as a guide for the location of the latter.

Before proceeding to describe the details of construction it may be stated that the inner clamp 8 which holds the upper sheet 10 is designed to be raised to release the primary sheet with considerable frequency and independently of the clamp 7 which holds the master sheet. Also it is desirable that when the clamp 8 is elevated the tape 12 be likewise raised so as to entirely free the sheet 10 to facilitate its displacement and its replacement by another sheet. In the arrangement shown this simultaneous raising of what may be termed the primary clamp 8 and the tape is effected automatically by the act of moving the machine back beyond the writing area. Furthermore, it is desirable that when the outer or secondary clamp 7 is raised to release the master sheet, the ribbon 11 be likewise raised to entirely clear the platen and avoid any interference with the displacement, replacement or adjustment of the sheet 9. For this reason the

ribbon and the clamp 7 are combined in an organization which effects the simultaneous movement of said clamp and ribbon away from the platen upon the operation of a key 18 located in the present instance at the front left hand corner of the platen. Obviously, however, when it is desired to replace the master sheet 9 the primary clamp 8 and the tape 12 must first be elevated. For this reason the secondary clamp 7 and the ribbon while elevated by means of the key 18, are locked against such movement as long as the primary clamp and the tape remain depressed, but are automatically released whenever the primary clamp 8 and the tape are raised. It will be seen, therefore, that the means for retaining the primary sheet on the platen may be operated independently of the secondary sheet retaining means and of the ribbon, but are so related to said secondary sheet retaining means and ribbon that the latter cannot be displaced from normal position until the primary sheet is released.

The outer or secondary clamp is carried at the upper ends of front and rear posts 19 and 20 passed downwardly through the platen and through bearing blocks 21 attached thereto. These posts are formed with racks 23 which engage front and rear pinions 24 mounted on shafts 25 and 25' journaled in the blocks 21. The shaft of the rear pinion 24 is a stub shaft similar to that shown in Fig. 5, while the shaft 25 of the front pinion is of considerable length and extends across the platen, as shown in Fig. 2, for a purpose to be hereinafter described.

Extended longitudinally of the platen beneath the same and passed through the blocks 21 is a comparatively long rack bar 26 toothed for engagement with the pinions 24 urged in a forward direction by a spring 27 bearing at one end against the rear block and at its opposite end against a collar 28 on the rack bar.

Mounted in a suitable bearing at the forward left hand corner of the platen is a bell crank key lever 29 the front end of which is equipped with the key 18 and the opposite end of which is disposed vertically and engages the front end of the rack bar 26. The spring 27 normally urges the rack bar in a direction to keep the clamp 7 depressed firmly upon the platen, but upon the depression of the key 18, the bar 26 is shifted rearwardly thereby rotating the pinions 24 which by their engagement with the posts 19 and 20 elevate the latter to raise the clamp 7 to its released position. To prevent the operation of the clamp 7 by the key 18 except when the primary work retaining means is in released position, as heretofore described, a locking lever 31 is fulcrumed on a bracket 32 at the rear left hand corner of the platen. The locking lever 31 is provided

with an angular arm 33 which is normally disposed in position to prevent the rearward movement of the rack bar 26, but is constantly urged to its bar releasing position shown in dotted lines in Fig. 8 by a spring 34. Normally, however, the locking arm 31 is held in its obstructing position against the resistance of its spring 34 by a roller 35 projecting through a longitudinal slot 36 in the bracket 32 and carried by a screw pin 37 which projects laterally from a second or inner rack bar 38 similar to the bar 26 but designed to operate the inner or primary clamp 8.

15 The inner rack bar 38 extends parallel with the bar 26 and passes through bearing blocks 21^a similar to the blocks 21 and is urged in a forward direction by a spring 27^a similar in construction and mounting to the spring 27. The rack bar 38 is also provided with teeth 39 which engage front and rear pinions 40 mounted in the blocks 21^a in a manner similar to the mounting of the pinions 24 in their respective blocks. The pinions 40 also mesh with teeth formed in front and rear posts 41 passed upward through the blocks 21^a and through the platen and supporting at their upper ends the primary clamp 8. When the inner rack bar 38 is in normal position, the clamp 8 is held firmly depressed and the locking lever 31 is held in the manner stated in position to prevent the operation of the secondary clamp 7 by the depression of the key 18.

35 It is designed to effect the automatic elevation of the primary clamp 8 and the consequent unlocking of the secondary clamp 7 by the act of moving the machine to the rear end of the platen. To accomplish these results, a machine-operated lever 42 is fulcrumed at its lower end upon the bracket 32 and has its upper end projected above the platen a sufficient distance to be engaged by the main frame 3 of the machine when the latter is thrown back to what is known as the machine support located in rear of the writing surface. At a point intermediate its ends the lever 42 bears against the roller 35 projecting from the inner rack bar 38, see 40 Figs. 8 and 9. Thus when the machine is moved back to the position indicated in dotted lines in Fig. 8, the lever 42 is swung rearwardly, thus urging the rack bar 38 rearwardly and causing the latter, through the intermediate gearing, to elevate the clamp 8. Simultaneous with this operation, to-wit the release of the primary or upper work sheet, the roller 35 recedes from the locking lever 31 thus permitting the spring 34 to swing said lever to the position indicated in dotted lines in Fig. 8 thus removing the angular obstructing end 33 of said lever from the path of the outer rack bar 26.

45 Thus the outer rack bar is released by the 50 operation of the primary clamp and may, if

desired, be operated by depression of the key 18 to elevate the outer or secondary clamp 7.

It has been stated that the tape 12 is designed to be raised away from the platen whenever the primary clamp 8 is operated. 55 This tape is attached at its rear end to a tension member 43 in the form of a bell crank lever fulcrumed on the platen 1 and having one arm connected to the tape and its opposite arm urged in a direction to exert tension on the tape by a tension spring 44. The front end of the tape 12 is connected to a tape carrier 45 located adjacent to the front end of the platen and comprising a top plate 45^a connecting the upper ends of 60 a pair of posts 46 which pass vertically through the platen and have their lower ends connected by a plate 47. One of the posts 46 is provided with rack teeth 48, see Fig. 3, which mesh with a toothed segment 49 carried by a transverse shaft 50 at the opposite end of which the front pinion 40 geared to the rack bar 38 is mounted.

When the lever 42 is operated by the machine to shift the rack bar 38 and elevate 65 the primary work clamp 8 the rotation of the pinions 40 will effect the swinging of the segment 47 through the medium of the shaft 50 thus elevating the front tape carrier and raising the tape 12 away from the 70 platen. The distance moved by the tape, however, is considerably greater than that of the clamp 8 by reason of the fact that the radius of the segment 47 which operates the tape carrier is considerably greater than 75 the radius of the pinions 40 which coact with the vertical supports or posts 41 of the clamp. The particular manner of mounting the shafts 25 and 50 is not material, but by reference to Figs. 2 and 3, it 80 will be seen that the ends of said shafts remote from the bearing blocks 21 and 21^a are supported by a bearing bracket 51 depending from the under side of the platen.

The ribbon 11, as stated, is designed to 85 be elevated when the secondary clamp 7 is raised. The ribbon is endless and passes around five rollers shown in Fig. 3 and numbered 52, 53, 54, 55 and 56. The rear roll 52 is mounted in a bracket 57 secured to the 90 rear end of the platen. The ribbon 12 passes around the rear side of this roller 52 which is of comparatively large size and passes thence over the platen, over and around the roller 53, thence in a vertical 95 direction to and around the roller 54, thence horizontally around the rear side of the roller 55, thence in an upward direction around the front side of the roller 56 and thence rearwardly to the roller 53, completing the endless circuit of the ribbon. The roller 55 is mounted on a shaft 58 afforded bearings in a bracket 59 depending from the platen somewhat in rear of its 100 front edge and said shaft 58 also supports 105

a swinging take-up or tension frame 60 of substantially inverted U-shape in which, at a point above the roller 55, the roller 56 is mounted. The upper end of the tension frame 60 is urged forwardly by a tension spring 61 to move the roller 56 in the proper direction to take up the slack in the ribbon 12 and exert a sufficient tension thereon to keep the same taut and smooth. The front 10 ribbon rollers 53 and 54 are mounted in the same vertical plane in a roller casing 62 mounted on what may be termed a ribbon carrier frame 63 secured to the opposite ends of a pair of vertical posts 64 and 65 passed vertically through the platen immediately adjacent to its front end and having rack teeth 66 for engagement with toothed segments 67 on the shaft 25. It will therefore appear that when the key 18 20 is depressed the rearward movement of the rack bar 26 will not only elevate the secondary work clamp 7, but will also through the medium of the front pinion 24 rotate the shaft 25 and swing the segments 67 to 25 elevate the ribbon carrying frame 63 and with it the ribbon 12 to the position indicated in dotted lines in Fig. 3. This will obviously remove the upper horizontal run of the ribbon from the writing surface of 30 the platen, carrying it a somewhat greater distance than that moved by the clamp 7 by reason of the difference in radius of the pinion 24 and the segments 67.

It is intended that this operation of the 35 ribbon carrying frame shall not only move the ribbon toward and from the writing surface, but shall also effect an automatic endwise feed of the ribbon to present unused portions of the latter at the printing point. 40 To this end the specified arrangement of the rollers is augmented by two detents 68 and 69 in the form of pivoted cams having knurled gripping faces 70 which coact with knurled disks 71 fixed to the ribbon guide 45 rollers 54 and 55. The detents 68 and 69 are mounted on the bracket 59 and on the roller casing 62 respectively, as shown in Fig. 4, and are urged into engagement with the disk 71 by springs 72. The detents 68 50 and 69 permit the rotation of the rolls 54 and 55 in a forward or clockwise direction, thus opposing no resistance to the rearward feed of that section of the ribbon lying between said rolls. Movement of these rolls 55 54 and 55 in the reverse direction, however, is prevented by the detents for a reason which will now become apparent.

It will be seen that when the ribbon carrier 63 is elevated, the upward movement of 60 the roll 54 is in a true vertical direction. Therefore, as the roller 55 remains stationary, both as to bodily translation and rotary movement, the distance between the rollers 54 and 55 will increase, this increase in the 65 length of the ribbon between these points

being compensated for by the rearward movement of the tension roller 56 to the position shown in dotted lines in Fig. 3. During this upward movement of the roller 54 the tendency of the latter will be to rotate 70 in the direction which is permitted by the detent 69. When the ribbon carrier 63 is dropped back to normal position, the distance between the rollers 54 and 55 decreases. There is a tendency, therefore, to create 75 slack in the ribbon between these rollers, but this tendency is counteracted first by the detent 69 which prevents reverse rotation by the roller 54 and second, by the take-up or tension device which is drawn forward 80 by the spring 61 to take up the slack which would otherwise be produced, the roller 55 rotating freely in the direction necessary to the taking up of this surplus ribbon between the rollers 54 and 55. It will thus be seen 85 that each operation of the ribbon raising and lowering mechanism will effect an endwise feed of the ribbon substantially equal to the difference between the length of that portion of the ribbon lying between the rolls 90 54 and 55 in the elevated and depressed positions of the roller 54, such feed being in the direction indicated by the arrow in Fig. 3.

It has been explained that successive primary sheets 10 are positioned on the platen by means of the scale 17 on the primary work clamp 8. It is obvious, however, that the printing mechanism must likewise be successively positioned in correspondence 95 with the successive positions of the sheets. It is therefore proposed to mount at the right hand side of the platen what may be termed a line space tabulator stop bar 73 substantially T-shaped in cross section, as 100 shown in Fig. 11, and formed at its under side with ratchet teeth 74. Movable longitudinally upon the rack 73 and formed with a T-shaped slot 75 to receive the same is a line space tabulator stop 76 equipped with 105 a holding device or detent 77 designed to feed between two of the teeth 74 and urged toward its engaging position by a spring 78 seated in the stop 76 and encircling a plunger 79 secured at its lower end to the detent 110 77 and having at its upper end a head 80 opposed to the upper end of the spring. At the outer side of the stop 76 is projected a finger piece 81 by means of which the detent 79 may be withdrawn from the teeth 74 of 115 the bar 73 when it is desired to shift the stop to a new position.

To facilitate the proper positioning of the stop 76 the upper face of the bar 73 is provided with a scale or graduations 82 corresponding as to spacing with the graduations on the clamp 8. At the initiation of the operation the sheets 9 and 10 are positioned by means of the top gages 13 and 15 and the stop 76 is properly positioned to arrest 120 125 130

the machine with its printing point properly disposed with reference to the primary sheet 10, it being observed that when the machine is drawn forward a portion of its structure, 5 as for instance one of the gibs 6, contacts with the stop 76. When the next primary sheet 10 is adjusted in an advanced position by means of the scale 17 and the clamp 8, the stop 76 is correspondingly advanced and 10 retained upon the bar 73. No attention need be paid thereafter to the positioning of the machine which is simply drawn forward until arrested by the stop, and the printing operation is resumed.

15 What I claim is:—

1. The combination with a platen and an endless transfer web, of relatively movable guides for said web, and means for effecting relative bodily movement of the guides to 20 feed the web.

2. The combination with a platen, of an endless transfer web, means for moving a portion only of said web toward and away from the platen, and means whereby such 25 movement of the web will effect a longitudinal feed thereof.

3. The combination with a platen, of an endless transfer web inclosing the platen, means for guiding a portion of said web 30 in a substantially straight path, and means for swinging said substantially straight portion of the web toward and from the platen.

4. The combination with a platen, of an endless transfer web and guides for said 35 web, one of said guides being movable to move a portion of the web toward and from the writing surface of the platen.

5. The combination with a platen, of an 40 endless transfer web inclosing the platen, a plurality of guides for the web, and means for effecting relative movement of the guides to move a portion of the web toward and from the platen and to effect a longitudinal feed of said web.

45 6. The combination with a flat platen, of a transfer web extended over the same, front and rear carriers for said transfer web, one of said carriers being movable to vary the distance between the carriers and to move 50 said web relative to the writing surface of the platen in a direction lateral to the web, and means coöperating with the carriers to effect an endwise feed of the web during the lateral movement thereof.

55 7. The combination with a flat platen, of an endless transfer web inclosing the platen, front and rear guides for the transfer web, said guides being relatively movable to shift the web toward and from the writing surface of the platen, and means coöperating 60 with the guides to effect a longitudinal feed of the web during the said shifting thereof.

8. The combination with a platen, of an 65 endless transfer web, guides for said web, and a tension device, certain of said guides

being relatively movable and coacting with the web and the tension device to effect a longitudinal feed of the web.

9. The combination with a flat platen, of an endless transfer web, front and rear carriers for said web, said front carrier being vertically movable, a relatively stationary guide engaging the web at a point intermediate of the front and rear carriers, and a tension device for the web. 70

10. The combination with a flat platen, of an endless transfer web, a rear guide for the web, a vertically movable web carrying frame, rollers carried by said frame and serving to guide the web, a guide engaging 80 the web at a point intermediate of the rear guide and the front web carrying frame, and a take-up or tension device engaging the web and holding the same taut under all conditions. 75

11. The combination with a platen and an endless transfer web, of guiding means for the web including a pair of guides relatively movable to effect an increase of the length of web extending between the same 90 and movable back to normal position to decrease the distance between said guides and thus create a surplus of material, and means for taking up said surplus of web to effect an endwise feed thereof. 95

12. The combination with a flat platen, of an endless transfer web, a rear guide roll therefor, front guide rolls located in the same vertical plane and movable vertically, a guide roll engaging the web intermediate 100 of the front and rear rolls, and a take-up or tension device engaging the web between the intermediate and rear guide rolls.

13. The combination with a platen and a transfer web disposed thereover, of means 105 including a key for moving the transfer web toward and from the platen, and means controlling the operation of the key.

14. The combination with a platen, of a transfer web disposed opposite said platen 110 and movable toward and from the same, and means for effecting both a longitudinal feed of the web and the movement of the web toward and from the platen.

15. The combination with a platen, of a 115 transfer web, and means including a key for effecting a longitudinal feed of the web and for moving said web toward and from the platen.

16. The combination with a platen, of an 120 endless transfer web, means for guiding a section of said web opposite the writing surface of the platen, and means for moving said web section toward and from the writing surface. 125

17. The combination with a platen, of an endless transfer web, guiding means retaining a section of said web opposite the writing surface of the platen, and means coacting with said guiding means to permit the 130

- movement of said web section toward and from the writing surface and to cause such movement of the web section to effect a longitudinal feed of the web.
- 5 18. The combination with a platen and a longitudinally movable transfer web, of means for guiding such movement of the web, and a key coacting with the guiding means to move the web.
- 10 19. The combination with a platen and a longitudinally movable transfer web, of means for guiding the web in such movement, and a key coacting with the guiding means to move the web toward and from the platen.
- 15 20. The combination with a platen and a transfer web, of guiding means for the web, and a key coacting with the guiding means to move the web longitudinally.
- 20 21. The combination with a platen and a transfer web, of guiding means for the web, and a key coacting with the guiding means to move the web toward and from the platen and to effect a longitudinal feed 25 of the web.
22. The combination with a flat platen, of a transfer web, means including a key for moving the web both laterally and longitudinally, and a lock for said key.
- 30 23. The combination with the relatively movable frame and platen of a typewriting machine, of a transfer web, means for moving the web, and a lock for said means, said lock being constructed and arranged to be 35 operated by the relative movement of the frame and platen.
24. The combination with a typewriting machine including a frame and platen one of which elements is movable relative to the other, of a transfer web, means for moving said web, and a lock for said means, said lock having a portion thereof extended into the path of movement of the movable typewriter element.
- 40 25. The combination with a typewriting machine including a frame and platen, one of said elements being movable relative to the other, a transfer web disposed opposite the writing surface of the platen, means for 45 moving said web laterally, and a lock for said means, said lock being disposed for actuation by the movable element of the typewriter.
- 50 26. The combination with a typewriter including a frame and platen one of which elements is movable relative to the other, of a transfer web, means for moving the transfer web away from the platen, and a lock for said means, said lock being disposed 55 for operation by the movable element of the typewriter.
- 60 27. The combination with a platen, of a transfer web disposed opposite the writing surface of the platen, a key for moving the transfer web away from the writing sur-
- face, a lock for said key, and a machine frame movable relative to the platen and coöperating with the lock.
28. The combination with a platen, of a transfer web and a work clamp both of 70 which are movable relative to the platen, and means for establishing an interdependent relation between the clamp and web.
29. The combination with a platen, of a transfer web and a work clamp disposed 75 opposite the platen, and means for moving both the clamp and the web relative to the platen.
30. The combination with a platen, of a transfer web and a work clamp disposed 80 opposite the platen, and means for moving both the clamp and the web relative to the platen, said means including a finger key.
31. The combination with a platen, of a transfer web and a work clamp opposite the 85 platen in parallel and laterally spaced relation, and means for moving both the clamp and the transfer web away from the platen.
32. The combination with a platen, of a transfer web and a work clamp opposite 90 the platen, and means for moving both the clamp and the transfer web away from the platen and for effecting the longitudinal feed of the web.
33. The combination with a platen, of a 95 work clamp and a transfer web disposed opposite said platen, and means including a finger key for moving both the clamp and the web away from the platen.
34. The combination with a platen, of a 100 work clamp and a transfer web disposed opposite thereto, both the clamp and the web being movable toward and from the platen, and reactive means for returning both the clamp and web to normal position when displaced therefrom.
35. The combination with a platen, of a 105 work clamp and a transfer web disposed opposite the same, means including a finger key for moving both the clamp and the web away from the platen, and reactive means for returning both the clamp and web to normal position.
36. The combination with a platen, of a 110 work clamp and a transfer web disposed opposite the platen, means for moving both the clamp and the web away from the platen, and a lock for said means.
37. The combination with a platen, of a 115 work clamp and a transfer web disposed 120 opposite the platen, means including a finger key for moving both the clamp and the web away from the platen, and a lock for the key.
38. The combination with a typewriting 125 machine including a frame and platen, one of which elements is movable relatively to the other, a work clamp and a transfer web disposed opposite the platen, means for moving both the clamp and the web rela-
- 130

tive to the platen, and a lock for said means constructed and arranged for release by the movable element of the typewriter.

39. The combination with a typewriting machine including a frame and platen, one of which elements is movable relative to the other, a work clamp and a transfer web disposed opposite the platen, means including a finger key for moving both the clamp 5 and the web relative to the platen, and a lock for said means constructed and arranged for release by the movable element of the typewriter.

40. The combination with a platen, of 15 primary and secondary work clamps disposed thereover to retain primary and secondary work sheets, a transfer element disposed over the platen to transfer the record from one sheet to the other, and a tape disposed over the transfer element to guard 20 one of the sheets.

41. The combination with a platen, of two separately movable work clamps adapted to retain work sheets, a transfer element coacting with the work sheets and movable 25 with one work clamp, and a flexible work guarding tape movable with the other clamp.

42. The combination with a flat platen, of a transfer element disposed thereover, 30 an inflexible work clamp extended along one edge of the platen, means for elevating both the work clamp and the transfer member and means including a part extended above the platen for controlling the elevation 35 of the clamp and transfer element.

In testimony whereof I affix my signature in presence of two witnesses.

HARRY A. FOOTHORAP.

Witnesses:

J. H. CULVERWELL,
R. M. PARKER.
